UNITED STATES PATENT OFFICE.

JOHN D. MYERS, OF PIKEVILLE, OHIO.

METALLIC RAILWAY CROSS-TIE AND RAIL-BRACE.

No. 838,044.

Specification of Letters Patent.

Patented Dec. 11, 1906.

Application filed August 18, 1906. Serial No. 331,160.

To all whom it may concern:

Be it known that I, JOHN D. MYERS, a citizen of the United States, residing at Pikeville, in the county of Darke and State of Ohio, have invented certain new and useful Improvements in Metallic Railway Cross-Ties and Rail-Braces, of which the following is a specification.

The invention has relation to an improvement in metallic railway cross-ties and rail-braces, the object being to produce a tie and brace of such a character as will combine the qualities of strength and durability and which when properly attached to the ordinary American or H steel rail of a railway-track will retain its position under heavy weights, will permit of the free expansion and contraction of the rails, will prevent the rails from spreading or careening, and will maintain the alinement and gage of the track under all conditions.

It is a further object of my invention to produce such a tie and brace from sheet metal and to provide simple and effectual means of attaching the rails and holding them in position on the tie.

These and other objects and advantages will more fully appear when taken in connection with the annexed drawings, of which—
30 Figure 1 is a top view of the tie and brace with rails attached. Fig. 2 represents an elevation of the tie and brace as they appear from the side and shows the construction of the tie when built in two sections and the method of attaching and bracing the rails. Fig. 3 represents the middle portion of the tie when built in one section. Fig. 4 is a bottom view of the tie. Fig. 5 is a top view of the rail-brace and shows the L-shaped slot necessary to its proper adjustment and the position of the bolts therein when attached to the rail. Figs. 6 and 7 represent, respectively, end and side views of the rail-brace and show the position of the attaching-bolts in the L-shaped slot.

Similar letters indicate similar parts in all of the figures.

Referring by letter to said drawings, A A indicate ordinary steel American or H rails of 50 a railway-track.

B B indicate my metallic railway cross-tie, which to conform to the gage of the track and the solidity of the road-bed may be of any desired length and width, constructed in two sections, having a top plate C C, formed either from one piece of metal

or by riveting or bolting to under plates a a metallic sheets b b b b of lighter weight, but in either event having equidistant from the ends of the tie and separated from each other a distance equal to the gage of the track transverse channels c c of sufficient width and depth to receive and conform to the base of the rails.

Metallic trusses d d, quadrangular in shape and having the ends turned or deflected in such manner as to form rests for the top plates C C and being equal in width thereto, are attached longitudinally to the under side of the top plates C C at e e e e by means of 60 rivets or bolts passing through the turned or deflected ends of the trusses and the top plates C C, the attachments being made on both sides of the channels c c, but in such manner as to leave space between the inner 70 ends of the trusses. This construction effectually prevents the tie from slipping endwise under the impact of heavy weights.

H-braces D D, conforming in length to the width of the top plates C C and the trusses 30 d d and constructed by riveting to plates f f channel-braces g g g g, are set transversely to the cross-tie directly beneath the channels c c and are attached to the top plates C C and lower portions of the trusses d d by 85 means of rivets or bolts, the rivets or bolts attaching these braces to the top plates C C, being countersunk therein to admit the base of the rails into the channels.

It will be noticed that the braces D D receive directly the force of any impact given 90 to the rails in a vertical direction.

To give further stability, Z-braces h h h h, formed from sheet metal and conforming in length to the width of the tie, are set transversely between the braces D D and the ends 95 of the trusses d d and are attached by rivets or bolts to the top plates C C and the lower portions of the trusses d d.

Bolts passing through the inner ends of top 100 plates C C and upper and lower plates i i unite the two sections of the tie. By this construction one-half of the tie may be removed from the track without disturbing the remaining portion thereof.

It is to be observed that the tie may be built in one section, Fig. 3 representing the middle portion of the top plate thereof when thus constructed.

The rail-brace, Figs. 5, 6, and 7, is formed 110 from sheet metal by a series of backward angular deflections in such manner as to con-

form to the channel of the rail and at the same time having the ends compressed together, one above the other, forming a base *j* with a lug *k* on the side of the lower portion 5 thereof, and having an L-shaped slot *l* cut transversely from the center of the base *j* to the center of the lug *k*, thence inwardly toward the rail, forming bolt rests or stops *m m m m*.

10 With the base of the rail resting in one of the channels *c c* of the cross-tie the brace is adjusted and firmly locked in position against the rail by means of bolts *n* and *o*, passing through holes in the top plates *C* and the extreme ends of the slot *l*, the bolt *n* being first inserted, as its free movement in the slot facilitates the adjustment of the brace to the rail.

15 It will be seen that the bolt *n* receives the force of any impact against the ball of the rail in a side direction, while the principal use of the bolt *o* is to lock the brace in position against the rail, and, if desired, may be omitted.

20 Cotter-pins *p p* are passed through the ends of bolts *n* and *o* on the outside of the nuts after the same are tightened and spread to afford further security.

25 I am aware that there are certain positions in which the rail-brace cannot be used for want of space, as between switch-points and the divergent rails of frogs. In such cases the rails may be secured to the tie by clamping heavy washers over the base of the rails by means of bolts passing through the top plate, or the rails may be attached thereto by use of bolt-spikes passing through square holes in the top plate.

30 When it is necessary to use cross-ties of extreme length, as among frogs and switches, the number of transverse channels in the top plate, as well as the number of truss-bearings, may be increased.

35 It is to be observed that the tie is adaptable to iron bridges, it being attached thereto by means of bolts passing through the bottom portion of trusses *d d* and the stringers of the bridge.

40 I have thus provided a combination of a railway cross-tie and rail-brace which may be constructed entirely from sheet metal, which combines the qualities of strength and durability, which permits of the free expansion and contraction of the rails without injury to the track, and, furthermore, when properly adjusted it will prevent the rails from spreading or careening and will maintain the alignment and gage of the track under all conditions.

45 Having described my invention, what I claim as new, and desire to secure by Letters Patent, is—

50 1. The combination with the American or H steel rail of a railway-track of a metallic railway cross-tie and rail-brace, the tie con-

sisting of a top plate, with transverse channels for the reception of the rails, resting on the deflected ends of quadrangular-shaped trusses attached longitudinally to the under side thereof, the top plate and trusses being supported by H-braces set transversely to the top plate directly beneath the channels therein, and Z-braces set transversely to the right and left thereof, all of which braces are attached to the top plate and the bottom portion of the trusses, and having metallic rail-braces each of which is constructed by a series of backward angular deflections in such manner as to conform to the channel of the rail, with the ends compressed together one above the other, forming a base, with a lug on the side of the lower portion thereof, and with an L-shaped slot cut transversely from the center of the base to the center of the lug, thence inwardly toward the rail, and attached by means of bolts passed through holes in the top plate, and the extreme ends of the slot, and locked with nuts and cotter-pins, all substantially as specified.

55 2. A metallic railway cross-tie consisting of a top plate with transverse channels for the reception of rails resting on metallic trusses quadrangular in shape with deflected ends forming rests, set longitudinally thereto, the deflected ends of each truss being attached to the under side of the top plate, the top plate and trusses being supported by H-braces set transversely to the top plate directly beneath the channels therein and Z-braces set transversely to the right and left thereof, all of which braces are attached to the top plate and the lower portion of the trusses, all substantially as set forth.

60 3. A rail-brace, formed from sheet metal by a series of backward angular deflections, in such manner as to conform to the channel of the rail, and having the ends compressed together, one above the other, forming a base or rest with a lug on the side of the lower portion thereof, and with an L-shaped slot cut transversely from the center of the base to the center of the lug; thence inwardly toward the rail forming rests or stops for bolts, and attached by means of bolts passed through holes in the top plate of the cross-tie and the extreme ends of the slots and locked with nuts and cotter-pins, all as set forth.

65 4. A metallic railway cross-tie having a top plate constructed in two sections by dividing transversely in the middle, the sections being united by upper and lower plates bolted through and across the inner ends thereof and having transverse channels for the reception of the rails, the top plate resting on quadrangular-shaped trusses, with deflected ends forming rests, set longitudinally thereto, the deflected ends of each truss being attached to the under side of the top plate, the top plate and trusses being sup-

ported by **H**-braces set transversely to the top plate directly beneath the channels therein, and **Z**-braces set, transversely, to the right and left thereof, all of which braces are attached to the top plate and the lower portion of the trusses, all as specified.

5. A metallic railway cross-tie having a top plate formed by riveting to a metallic under plate metallic sheets of lighter weight, but in such manner as to leave transverse channels for the reception of the rails, the top plate resting on the deflected ends of quadrangular-shaped trusses, attached longi-

tudinally to the under side thereof, the top plate and trusses being supported by **H**-braces set transversely to the top plate directly beneath the channels therein, and **Z**-braces set, transversely, to the right and left thereof, all of which braces are attached to the top plate and the bottom portion of the trusses, all as set forth.

JOHN D. MYERS.
